United States Patent

Des. 239,580

Patented Apr. 20, 1976

239,580

SOFA OR THE LIKE

Stephen H. Robertson, 4108 Deep Hollow Drive, Apt. 277, and Randall L. Ward, 4102 Deep Hollow Drive, Apt.
284, both of Raleigh, N.C. 27612

Filed Feb. 18, 1975, Ser. No. 550,527

Term of patent 14 years

Int. Cl. D6—01

U.S. Cl. D6—63

FIG. 1

FIG. 2

FIG. 1 is a front end perspective of a sofa or the like showing my new design; and

FIG. 2 is a rear end perspective view of such design.

The bottom of the sofa or the like is substantially plain and unornamented.

We claim:

The ornamental design for a sofa or the like, as shown and described.
